UNITED STATES PATENT OFFICE.

RICHARD WEBB BURNETT, OF MONTREAL, QUEBEC, CANADA.

GRAIN-CAR DOOR.

1,255,382.

Specification of Letters Patent.

Patented Feb. 5, 1918.

Application filed August 10, 1914. Serial No. 856,106.

To all whom it may concern:

Be it known that I, RICHARD WEBB BURNETT, a citizen of the United States of America, residing in the city of Montreal, Province of Quebec, Dominion of Canada, have invented certain new and useful Improvements in Grain-Car Doors; and I do hereby declare that the following is a full, clear, and exact description of the same.

10 My invention relates more particularly to displaceable door-jams which are adapted to when in one position retain a removable door in closed position and when the door is opened or removed be moved to a position 15 affording practically full clearance through the door opening.

The invention may be said briefly to consist of a hinged or pivoted door-jamb, the axis of which is near the outer wall of the 20 car, a door-jamb receptacle being carried by the door-post in position to receive the door-jamb when swung from door-retaining position and a vertical slidable key carried by the door-post adapted to lock the door-jamb in either position.

For full comprehension, however, of my invention reference must be had to the accompanying drawings forming a part of this specification, in which similar reference characters indicate the same parts, and 30 wherein:

Figure 1 is a horizontal sectional view taken on line A A Fig. 4 and illustrating a portion of a car side with removable grain door and my improved means for retaining and locking the removable grain door in place;

Fig. 2 is a similar view to Fig. 1 of the side of the door carrying my improved door 40 retaining means illustrated in different position;

Fig. 3 is a similar view to Fig. 1, the section being taken on line C C Fig. 4; and

Fig. 4 is a vertical sectional view taken 45 on line B B Fig. 1 and illustrating in a fragmentary way the upper portion of the door-frame, the grain door and my improved door retaining means;

Fig. 5 is a similar view to Fig. 4 of the 50 lower portion of the door frame, etc.;

Fig. 6 is a detail face view of the device for containing the key and under certain conditions reinforcing the door-jamb;

Fig. 7 is a sectional perspective view illustrating the door-jamb locked in door sup-

porting position according to my invention; and

Fig. 8 is a perspective view of the key removed.

As will be seen on the drawings my locking means comprise a door-jamb of angular cross-section having one side pivoted such jamb being received by a receptacle in the form of a channel-iron and a vertically movable key serving to lock the door-jamb 60 in either door-retaining position or within the receptacle.

The sheathing or wall of the car is indicated at *b*, the door-post at *c*, removable grain-door at *d*, door-jamb above referred 70 to at *e*, the receptacle at *f* and the key at *g*. The specific construction of the door-jamb consists of a plate folded back upon itself to present a stiffened or reinforced portion *e*¹ extending from its free edge to within 75 close proximity to its pivot, the latter being constituted by a pair of substantially half round bars *e*² fastened to the opposite sides of the inner edge portion of the door-jamb, the lower end of these bars acting as a 80 hinge pin *e*³ pivoted in a threshold angle *e*⁴ carried as usual by a side-sill *e*⁵. The lower end of the jamb is cut away to afford the hinge pin. The floor *e*⁶, also as usual, is carried by the side-sill and the surface 85 thereof is flush with the surface of the threshold angle. The upper end of the pivot is rotatably set in a socket *e*⁷ cast with an attachment flange *e*⁸ by which it is fastened to the door-post by rivets *e*⁹ through a channel iron *f*. This flange extends laterally and upwardly from the socket which is also cast with a pair of angular flanges *e*¹⁰ upon its face serving as a guide for the key *g*.

A pressed shape of irregular channel form 90 is secured to the door-post angle *k* the upper half *f* of which is narrower than the lower half *f*¹ but one side edge of the upper half being in vertical alinement with the corresponding edge on the lower half. This 100 side has a continuous flange *f*², the flange *f*³ at the opposite side of the upper portion being equal in width to the flange *f*² and the flange *f*⁴ of the lower portion being of reduced width acting as a stop or support for 105 the door-jamb when it is swung to a position releasing the door. The door-jamb is adapted to bear against this flange *f*⁴ thus reinforcing the former and making a grain tight joint. The door-jamb when open lies 110

substantially parallel to the web of the channel and behind the flange f^2 outwardly relatively to the car side.

The door-jamb as before mentioned is held in door retaining position and position closing the door by the key g . This key consists of a comparatively heavy bolt slidably retained in the slideway formed by the flanges e^{10} and having its upper end turned outwardly as at g^1 and its lower end provided with a lug g^2 , to prevent upward withdrawal of the key. This key and its guiding flanges are constructed and arranged to have one edge of the key support the reinforced portion e^1 of the door-jamb when the latter is in position supporting the grain door and clamp the door-jamb within the receptacle formed by the portion f of the channel when the grain door is displaced. The door is retained against inward displacement by stops m one only of which is illustrated in the drawings.

The manner of pivoting the door-jamb permits it to rest at all times on the threshold plate thus making a grain tight joint at this point; and the particular arrangement of channel f with its flange f^2 located a short distance from the edge of the door-post angle c affords a jamb for the outside door not shown when closed thus making a weather and spark-proof joint between outside door and door-post when the door is closed.

The plate forming the door-jamb presents an obtuse angle in cross-section in order to cause it to have its reinforced edge lie in proper door-retaining position and to lie parallel to the web of channel iron f when swung to position clearing the door. The advantage of this arrangement of parts is that the whole is confined within comparatively small limits.

The lower end of the flange f^3 and a portion of the web of f are cut away the latter forming an opening f^{10} to accommodate the back of the casting to permit it to be set back and bring the top pivot of the door-jamb

flush with the web of the channel and in close proximity to the door post and flange f^4 . The side of the casting forms a continuation of the flange f^3 and together they form a rigid jamb for the upper grain-door.

What I claim is as follows:—

1. The combination with the side of a car having an opening and a door adapted to be moved through said opening, of a door-jamb constructed and arranged to support the door in closed position and be moved to a position clearing the door, of unitary means whereby the said door-jamb is locked in both door-supporting and door-clearing positions, said means consisting of a vertically slidable key adapted to lie in flat contact with the said door-jamb when locking the same.

2. The combination with the side of a car having a door opening, a door, and a door-jamb for the door and pivoted at its lower end in the door opening, of a unitary homogeneous member located above the door-jamb and having a socket and keyway the upper end of the door-jamb being pivoted in such socket and a key slidably mounted in said keyway for locking the door-jamb.

3. The combination with the side of a car having an opening and a door adapted to be moved through said opening, of a door-jamb constructed and arranged to support the door in closed position and be moved to a position clearing said door, of means whereby the said door-jamb is locked in both door-supporting and door-clearing positions, said locking means being constructed and arranged to assume the same position when locking the door-jamb in door-clearing position as in door-supporting position.

In testimony whereof I have signed my name to this specification in the presence of two witnesses.

RICHARD WEBB BURNETT.
